SIFTER HAVING AGITATOR BODIES

James F. Barnes, Chicago, Ill.

Application June 1, 1948, Serial No. 30,424

3 Claims. (Cl. 209—323)

1

This invention relates to a sifter. The invention is particularly useful as a sifter of flour and similar granular or fluid particle material.

An object of the invention is to provide a portable sifter employing a multiple stop action principle which subjects the flour, etc., upon the screen to a large number of short quick stops or jerks and results in the rapid sieving of the flour. Yet another object is to provide a structure in which balls, disks, squares, cubes or other freely-moving objects are employed in a sifting vessel for rolling flour upon a screen, while at the same time striking the sifter casing to jolt the structure during the sifting operation. Yet another object is to provide such a sifter equipped with a handle mounted for limited movement which similarly subjects the sifter to quick stopping or jolting movements. Other specific objects and advantages will appear as the specification proceeds.

The invention is illustrated in a specific embodiment by the accompanying drawing, in which—

Fig. 1 is a top plan view of a sifter embodying my invention, a portion of the structure being broken away and shown in section; Fig. 2, a vertical sectional view, the section being taken as indicated at line 2—2 of Fig. 1; Fig. 3, a top plan view of a modified form of sifter embodying my invention; and Fig. 4, a transverse sectional view, the section being taken as indicated at line 4—4 of Fig. 3.

In the illustration given in Figs. 1 and 2, 10 designates a vessel which may be formed of plastic, metal, or any other suitable material. The vessel 10 is provided with an open bottom in which is mounted a screen 11. The screen may be supported by any suitable means. In the specific illustration given, the screen is clamped between a depending skirt member 12 of the vessel 10 and a ring member 13. The ring member 13 is provided with an inwardly-crimped portion 14 serving to clamp the screen tightly in position, as illustrated in Fig. 2. Preferably, the ring or collar 13 is formed of plastic, and integrally molded therewith is a bracket arm 15 providing a socket or seat 16. In the socket 16 is mounted a tubular handle 17. The upper end of the handle is received within a tubular socket 18 provided by a bracket arm 19 formed integrally with the vessel 10, as shown more clearly in Fig. 2.

The socket portion 18 of the arm 19 is preferably provided with an inwardly-turned stop lug 20, as shown more clearly in Figs. 1 and 2. The handle 17 is cut away at 21 to provide for angular movement of the handle relative to the stop lug 20. In other words, the vessel 10 and bracket arm 19 may swing relative to the handle 17 for the distance of the arcuate cutaway portion 21. At the end of each swinging movement, the lug 20 strikes the shoulder of the handle 17 and

brings about a sudden stop to the swinging movement of the vessel 10.

Upon the screen 11, I mount a plurality of balls 22. The balls may be allowed to roll in any direction over the flour supported by the sieve or screen 11. In the specific illustration given, the balls 22 are guided for lateral movement by the transverse strips 23 so that the balls are required to move laterally, striking the sides of the vessel 10. While the vessel is shown to be in a generally square shape, it will be understood that any suitable shape may be provided. The transverse strips 23 are buttressed and supported by the strips 24 running in the opposite direction, as shown more clearly in Fig. 1. The strips 23 and 24 may be formed of plastic or any other suitable material.

While I have shown a single ball mounted in each of the transverse paths controlled by the strips 23, it will be understood that there may be more than one ball in each path, and further that such paths may be modified in contour as desired.

If desired, the vessel 10 may be provided with inwardly-extending vertical ribs 25 which intermesh with recesses 26 carried by the open network or plate member 27 with which the transverse strips 23 and 24 are formed in plastic or other suitable material.

In the operation of the structure, the flour is dropped within the vessel 10 and it finds its way through the network strips 24 and 23 into the chamber above the screen 11. As the handle 17 is moved in one direction and halted, the vessel 10 swings about the handle until the stop lug 20 thereof engages the shoulder to one side of the cutaway arc 21 of handle 17. Movement of the handle in the opposite direction and the stopping thereof causes the vessel 10 to swing in the opposite direction until the lug 20 strikes the shoulder at the other end of the arc 21. Simultaneously with the above movement, the balls 22 roll across the transverse paths in engagement with the flour and tend to move the flour through the sieve. Further, as the balls strike the opposite side of the vessel 10, they vibrate or shake the vessel so as to effect a further shifting of the flour upon the sieve 11.

It will be seen from the above that there are four distinct actions which bring about a shifting of the flour upon the sieve 11 to effect a sieving action. There is first the normal side movement of the vessel 10, which produces a shifting of the flour upon the screen 11. Secondly, the striking of the stop lug 20 of the vessel arm 19 against the shoulders of the handle 17 on either side of recess 21 brings the vessel 10 to sudden stops and effects a movement of the flour upon the screen. Thirdly, there is the movement of the rollers or balls 22 across the sieve which engage the flour and moves the flour while at the

same time vibrating the screen. And finally, there is the sudden jolting action given by the balls 22 as they successively or simultaneously strike the walls of the container 10. While the only movement given by the operator is that of swinging the handle 17 back and forth, the result is a composite shaking of the structure so that the flour moves many times over surfaces of the screen 11 during a single swinging of the handle. The result is that an effective sieving of the flour is accomplished in a considerably reduced period while at the same time a more thorough sieving action is brought about because of the quick short movement of flour particles over areas of the sieve. For example, one movement of the balls 22 across the screen to the opposite side of the vessel usually brings about a succession of impacts as the balls strike the vessel wall at slightly different times, yet each of the impacts is effective for a slight moving of flour particles over a small portion of the screen. I have further found that the balls 22 thus exert an important influence upon the sieving action in that they physically move the flour from side to side while vibrating the screen as they move along it so as to shift flour particles for short distances on the screen.

In the modification illustrated in Figs. 3 and 4, the body 10a is equipped with a central partition wall 30. The transverse guides 23a provide relatively short courses for the balls 22a, as shown more clearly in Fig. 4, and the members 23 may, if desired, be reinforced along their top surfaces with the cross strips 24. I prefer to form the central partition 30, as illustrated more clearly in Fig. 4, and each of the cross strips 23a and 24 with a rounded or teardrop-shaped top surface 31 so that the flour, etc. slides readily over the network of such members and into the chamber below where the balls 22a travel over the screen 11a.

The body 10a is provided with an integrally extending rear arm 32 to which is fixably secured a handle 33. Thus, there is no relative movement between the handle and the fixed structure of the sifter. By providing such a rigid connection between the handle and sifter, I find that more effective control of the balls 22a can be obtained; and, in fact, I prefer to employ a fixed handle in connection with the structure illustrated in Figs. 1 and 2.

The retaining ring for the screen in either of the structures may be molded as an integral part of the product. If desired, the screen itself may be molded so that the entire body consisting of the receptacle, the handle, and the screen, are formed in a unitary structure and in one molding operation.

It will be understood that my invention may be employed with all or only a portion of the vibrating structures described, effective results being obtained with less than all of the shaking devices combined in the structure illustrated.

While in the foregoing specification, I have shown a specific structure in considerable detail for the purpose of illustrating one embodiment of the invention, it will be understood that such details of structure may be varied widely by those skilled in the art without departing from the spirit of my invention.

I claim:

1. A sifter, comprising a vessel which is gen-

erally square-shaped in horizontal cross section, a handle extending laterally from one side of said vessel, said vessel having an open bottom, a screen mounted in said bottom of the vessel, a partition wall extending over said screen and upwardly therefrom and generally through a central portion of the screen, a reticulate frame carried by said vessel above said partition and supporting the upper portion of said partition wall, depending guides carried by said frame and extending transversely of said vessel to form with said partition wall two rows of parallel transverse guideways, and a single ball in each guideway, whereby said balls can be caused to strike the sides of said vessel and thereby vibrate said screen by rapidly moving said sifter through a generally horizontal plane and then suddenly ceasing the movement thereof.

2. A sifter, comprising a vessel which is generally square-shaped in horizontal cross-section, a handle extending laterally from one side of said vessel, said vessel having an open bottom, a screen mounted in said bottom of the vessel, a partition wall extending over said screen and upwardly therefrom and generally through a central portion of the screen, a reticulate frame carried by said vessel above said partition and supporting the upper portion of said partition wall, depending guides carried by said frame and extending transversely of said vessel to form with said partition wall two rows of parallel transverse guideways, and a single ball in each guideway, whereby said balls can be caused to strike the sides of said vessel and thereby vibrate said screen by rapidly moving said sifter through a generally horizontal plane and then suddenly ceasing the movement thereof.

3. A sifter, comprising a vessel having an open bottom, a screen mounted in said bottom of the vessel, a partition wall extending over said screen, a reticulate frame carried by said vessel above said partition, depending guides carried by said frame in horizontal parallel lines transversely of said vessel to form rows of parallel transverse guideways, said guides terminating short of said screen and providing parallel trackways transversely of the screen, and balls in said trackway confined by said depending guides against movement through an arc of more than 90°, whereby said balls can be caused to strike the sides of the vessel and thereby vibrate said screen by rapidly moving said sifter through a generally horizontal plane and then suddenly ceasing the movement thereof.

JAMES F. BARNES.
